UNITED STATES PATENT OFFICE.

JAMES A. KEYES, OF NEW YORK, N. Y.

ELECTRIC SWITCH.

1,166,055.

Specification of Letters Patent. Patented Dec. 28, 1915.

Application filed March 21, 1912. Serial No. 685,339.

To all whom it may concern:

Be it known that I, JAMES A. KEYES, a citizen of the United States, and resident of the city, county, and State of New York, have invented certain new and useful Improvements in Electric Switches, of which the following is a specification.

This invention relates to an electric switch, the object being to provide a switch having a quick make and break and adapted to be operated by any exterior moving member, such as a door.

In carrying out the invention I provide a pair of contacts to which the line terminals are attached. A circuit closing member is arranged to be held either out of or in engagement with the contact members. Means are provided for releasing the contact member and for causing the same to quickly move or snap into or out of engagement with the line terminals.

In the drawings, in which is illustrated one operative embodiment of my invention, like parts in the several views have been given the same reference numerals.

Figure 1 is a sectional side elevation of a switch embodying the invention, the section being taken on the line 1—1 of Fig. 2. Fig. 2 is a sectional plan view of Fig. 1, taken on the line 2—2 of Fig. 1. Fig. 3 is a sectional end view, taken on the line 3—3 of Fig. 2.

A base 1 is provided with upwardly extending end portions and with a cover 2 which inclose the operating mechanism of the switch. The base 1 may also be provided with an upwardly extending support 3 upon which the line terminals 4 and 5 are insulatedly mounted. A circuit closing member, comprising a contact member 6 insulatedly mounted upon a lever 7, is pivotally attached to the support 3.

The lever 7 is provided with an extension 8 having oppositely inclined faces at its upper end adapted to be engaged by the latch 9 which is pivotally mounted upon the support 3 and normally held in engagement with one of the inclined faces by means of the spring 10. The member 8 also carries a pin 11 which is positioned to be engaged by the collars 12 and 13 upon a sliding operating member 14. The sliding member 14 is supported in the vertical end portions of the base 1 and is provided with adjusting nuts 15 at one end and with a spring 16 positioned about the member 14 and compressed against one end of the base 1 and the collar

13. In the position shown in the drawings the sliding member 14 is assumed to have been moved and held against the pressure of the spring 16 by the door or other movable member with which it is used. In the position shown the contact 6 is held out of engagement with the line terminals 4 and 5 and the circuit open, the contact member being held in its open position by means of the latch 9 engaging one of the inclined faces of the extension 8 of the lever 7. When the member 14 is released by the movement of the door, the spring 16 causes the same to move to the left from its position shown in Figs. 1 and 2 and this movement causes the collar 13 to engage the pin 11 and force the member 8 under the latch 9. As soon as the latch 9 passes over the apex of the member 8, its engagement and pressure upon the opposite side of the inclined face of the extension 8 causes the contact member to snap quickly into its closed position and close the circuit through the line terminals 4 and 5 and contact 6. When the sliding member 14 is moved to the right the collar 12 engages the pin 11 and causes the extension 8 to pass under the latch 9 in the opposite direction. The engagement of the latch 9 with the opposite inclined face of the extension 8 causes the contact member to be snapped quickly into its open position, resting against the stop 17 and opening the circuit between the line terminals 4 and 5.

It will thus be seen that a quick make and break switch is provided which is simple in its construction and positive in its operation.

What I claim is:

In an electric switch, in combination, a pair of line terminals, a fixed circuit-closing member and a movable circuit closing member adapted to close the circuit between said line terminal, a support, a spring pressed hooked-shaped latch pivoted on said support adapted to hold said member in and out of electrical connection with said terminals, said movable circuit closing member having at its pivoted end an extended portion provided with oppositely inclined faces adapted to be engaged by said hooked-shaped latch whereby when the same is released its movement either into or out of engagement with said terminals is accelerated, a movable operating member provided with a pair of spaced collars adapted to be moved in one direction by external means, a spring engaging one of said collars causing said operating members

to be returned to its original position automatically when released by said means, a pin on said extended portion, said collar adapted to engage said pin to cause said inclined portions to pass under said latch in either direction whereby the same is operated.

Signed at New York city, in the county

and State of New York, this 14th day of March, 1912.

JAMES A. KEYES.
